UNITED STATES PATENT OFFICE.

ROBERT M. LOCKWOOD AND SAMUEL H. BARTLETT, OF NEW YORK, N. Y.,
ASSIGNORS OF ONE-HALF OF THEIR RIGHT TO CHARLES F. LIVERMORE,
OF SAME PLACE.

TRANSMITTER AND REPEATER FOR TELEPHONES.

SPECIFICATION forming part of Letters Patent No. 229,151, dated June 22, 1880.

Application filed March 9, 1880. (No model.)

To all whom it may concern:

Be it known that we, ROBERT M. LOCKWOOD and SAMUEL H. BARTLETT, of the city, county, and State of New York, have invented certain new and useful Improvements in Transmitters and Repeaters for Telephones or Vocal Telegraphs, of which the following is a full, clear, and exact description, reference being had to the accompanying drawings, making part of this specification, in which—

Figure 1 represents a vertical section through our improved transmitting apparatus. Fig. 2 is a similar view of the same apparatus arranged to act as a repeater; and Fig. 3 is a perspective view of the magnet, carbon, or conducting plates or bars and insulators detached or removed from the non-resonant block.

Similar letters of reference denote corresponding parts wherever used.

Our invention relates to a novel construction of transmitter for telephones or vocal telegraphs, whereby said transmitter is adapted also to act as a repeater for repeating the vocal sounds and sending over new main-line wires with independent batteries, as herein-after described.

In telephones as heretofore constructed, so far as we are aware, reliance for the transmission of sounds has been placed mainly on the induced current, and great difficulty has been experienced in the use of this current, for the reason that it is weak and uncertain in its action and liable to jump from the conducting-wires to neighboring conductors or wires.

This current has been employed in preference to the direct or battery current on account of the extremely delicate or sensitive diaphragms or equivalent devices used for the reception of the sound-waves, which rendered it impracticable to use a direct current of sufficient power to transmit the vocal sounds to any considerable distance, owing to the fact that in the use of such current the diaphragms employed are firmly grasped and held by the interposed magnet, and their further vibration under the action of the sound-waves is checked, rendering them practically inoperative for the purpose intended.

The construction of transmitter by which we dispense with this diaphragm and the mechanical vibration referred to, thereby enabling us to use the direct current, is set forth in another application of even date herewith. Our improvement thereon, herein described, consists in adding to the transmitter, consisting of the non-resonant block with its carbon bars or plates and button therein described, a magnet and helices interposed in the block in the main-line current, thereby greatly increasing its power as a transmitter and adapting it, with a proper adjustment or arrangement of the connecting-wires, to act as a repeater, for taking up and repeating a vocal telegram to a new circuit or circuits forming extensions of the first, and operated by independent batteries, as in the case of ordinary telegraphic communication.

In the accompanying drawings, A represents a base-plate of wood or other suitable material, upon which is secured a block, B, of cork or other non-resonant material, made either polygonal or cylindrical in form, that shown approximating the form of a cube. Near its upper end the block B has strips or bars *b b'*, of carbon or other suitable conducting material, embedded in it, said strips extending transversely across the block from the sides to near the center, where they are separated by a short intervening space, a button, *b²*, serving to bridge said space and connect the two bars, in a manner similar to that described in another application filed herewith. Underneath the plates *b b'* are placed strips or plates *c c'*, of rubber or other non-conducting material, resting over the arms *d d'* of a magnet, D, said arms penetrating the base-plate A and block B, with their ends resting in contact with the insulators *c c'*. Wooden pins *e e'* pass through the carbon and insulating plates into sockets in the ends of the magnet, connecting the carbon plates therewith and preventing displacement of the parts.

In order to afford access to the removable button *b²*, an aperture is made in the block B directly over said button, which, when the parts are in place, is filled by a plug, *B'*, of

non-resonant material, similar to that of which the block is formed.

Suitable cavities or pockets are formed in the block B, around the ends of the arms d d' of the magnet, for the reception of spools or helices F F', one upon each arm, directly under the insulators, as shown, these helices being formed in the usual or any preferred manner.

The base-plate A has suitable screw or binding posts G G' applied to it for facilitating the attachment, removal, or transfer of the wires, the same as in an ordinary telegraphing-instrument, the eyebolts or pins g g' representing the points of attachment of the main-line wires to said posts.

In the arrangement of the devices as a transmitter simply, as shown in Fig. 1, the wires of the apparatus *per se* are arranged as follows: A short wire, h, extends from the screw-post G up to and is united to the carbon or conducting plate b in any suitable manner, said wire terminating at said plate. From the opposite end of plate b' proceeds a second wire, h', which passes downward outside the block to the plane of the lower end of helix F', where it penetrates the block, and, wrapping the spool in the usual manner, forms said helix, after which it passes through the intervening partition a of the block to and wraps the second spool, forming the helix F in the same manner. From this point the wire passes out through a perforation in the block opposite to where it entered, and thence around said block and down to the screw-post G', where its end is secured in any preferred manner. By now attaching the main-line wires and the battery with the connecting pins g g' in the screw-posts, the same as in a telegraph-instrument, the apparatus, as a transmitter, is complete and ready for action. The sounds are received upon the surface of the non-resonant block B, and thence, through what we term "molecular" and electrical action, are transmitted to the carbon or conducting bars firmly fastened to or embedded in the block; thence to the intervening button, resting thereon by its own weight, molecularly agitating or disturbing the latter. The button being in the main-line current, the latter is correspondingly disturbed, and the molecular disturbance of the button being in unison with the sound-waves received upon the surface of the block B, the latter are transmitted over the wires to the desired point.

In Fig. 2 we have shown a similar apparatus arranged to act as a repeater, the construction being the same as in the case of the transmitter, Fig. 1, the difference between the two consisting in the arrangement of the wires. The main-line wires from the transmitter connect with the pins g g', and thence through the screw-posts G G' and wire h', which corresponds with the wire h' of Fig. 1 in that it extends from the post G' through the block forming the helices F F'; but instead of connecting di-

rectly with the carbon, as in Fig. 1, it passes down to the screw-post G, and thus completes the first main-line circuit. The action of the disturbed electric current upon the magnet in passing over the helices F F' causes similar molecular disturbance of the magnet, which, in turn, is transmitted through the non-resonant body B and pins e e' to the carbon plates b b', and thence to the button b², (which to distinguish it from button b¹, Fig. 1, is designated b³), and the disturbance of the latter coincides exactly with that of the button b², and, being connected in like manner with new line-wires and battery, repeats the message, and so on, running through the requisite series of circuits with similar repeaters until the message is delivered at the desired point.

By this arrangement of repeaters and batteries with extending circuits we are enabled to utilize the direct current, and thereby to transmit vocal sounds any required distance, with the same precision and in like manner as ordinary telegraphic communications are now sent, differing only in the transmitting, repeating, and receiving devices.

The non-resonant block, with its embedded conductors, and provided with the magnet, as described, answers well also as a receiver, and may be used as such. Another and preferred form of receiver is, however, described in another application of even date herewith.

The sleeves described in another application filed herewith for destroying the induction-current may be employed also with the helices F F' with like beneficial results.

We are aware that it is not new to use carbon contacts for repeating from one circuit to another of a telephone-line, and we make no claim, broadly, to the same; but our invention differs from any previous arrangement of which we are aware in that we use no armature or diaphragm between the magnet and the carbon.

Having now described our invention, we claim—

1. The non-resonant block in which the carbon or conducting plates are secured, in combination with a magnet or magnets applied thereto, substantially as described.
2. The non-resonant block provided with the carbon plates and interposed button, in combination with the magnet and helices applied thereto and operating substantially as described.
3. The combination of a non-resonant block, strips, and button of carbon or equivalent conducting material and a magnet arranged and operating substantially as described.
4. The carbon bars or conductors, separated from the magnet by insulators, in combination with the wooden pins penetrating the insulators and connecting the carbon bar or plates with the magnet, substantially as described.
5. The combination, in a vocal-sound transmitter or repeater, of immovably embedded

carbon strips or conductors and a magnet, either permanent or electro-magnetic, the helices of which, together with the carbon strips, are adapted to be interposed in the direct or main-line current, substantially as described.

6. The combination, with the non-resonant block B, of the magnet D, helices F F', carbon bars or conductors b b', interposed button, in-

sulators c c', and connecting-pins e e', all arranged substantially as and for the purpose so described.
